DESIGN FOR AN ADVERTISING DISPLAY DEVICE FOR OPHTHALMIC MOUNTINGS

Edward M. Splaine, Southbridge, Mass., assignor to American Optical Company, Southbridge, Mass., a voluntary association of Massachusetts

Application September 30, 1937, Serial No. 71,868

Term of patent 14 years

To all whom it may concern:

Be it known that I, Edward M. Splaine, a citizen of the United States of America, residing at Southbridge, in the county of Worcester and State of Massachusetts, have invented a new, original, and ornamental Design for an Advertising Display Device for Ophthalmic Mountings, of which the following is a specification, reference being made to the accompanying drawing, forming a part thereof.

Fig. I is a perspective view of an advertising display device for ophthalmic mountings showing my new design; and

Fig. II is an end view of the design shown in Fig. I.

The characteristic features of the design consist in a base having a support thereon for displaying ophthalmic mountings.

I claim:

The ornamental design for an advertising display device for ophthalmic mountings substantially as shown and described.

EDWARD M. SPLAINE.
